UNITED STATES PATENT OFFICE.

CARLO SERRA, OF NEW YORK, N. Y.

MESSAGE-SHELL.

1,356,746.

Specification of Letters Patent. Patented Oct. 26, 1920.

Application filed January 15, 1920. Serial No. 351,710.

To all whom it may concern:

Be it known that I, CARLO SERRA, a citizen of the United States of America, residing at New York, in the county and 5 State of New York, have invented certain new and useful Improvements in Message-Shells, of which the following is a full, clear, and exact description.

This invention relates to an apparatus 10 for sending and receiving messages by means of projectiles and has for its object the provision of a message shell of such character that it may be despatched in any convenient manner as by an explosion of 15 powder from a gun or by compressed air or otherwise. The invention particularly contemplates the provision of a shell of such character that it will, when received, at the receiving station, be accessible to the 20 recipients and will not bury itself in the ground or otherwise damage itself so as to mutilate the message contained therein or render it necessary to excavate the ground for the received shell.

25 In order that the shell may be thus received, the invention contemplates the provision of a receiving station of such character that it will yield to the shock of the impact of the received shell and also prevent a surface which will entangle certain 30 entangling means on the shell so that the projectile will thereafter depend from the forward face of the receiving station in position to be accessible to the recipients.

35 The invention further contemplates a message shell having entangling projections which portion of the shell is removable from the remainder of the shell in order that the shell may be used again should the entangling 40 projections be damaged, or be so entangled in the entangling means as to be impossible of being extricated therefrom.

Other objects will be set forth in detail in the accompanying specification and shown 45 in the drawings in which—

Figure 1 shows the receiving station with a number of shells entangled thereat and a shell in flight thereto.

Fig. 2 is a detail partly sectional view of 50 the message shell.

The shell comprises a hollow body portion 10 adapted to receive the messages and having a removable closure 11 for one end thereof which is preferably threaded to the 55 body portion. The shell has a nose portion 12 having a pointed nose and a plurality

of entangling pins or projections therein 13 disposed between the nose portion and the body portion. These projections have pointed ends and are arranged indiscriminately 60 without regard to the direction of the points. The shank portions of the projections are preferably threaded into the body 12, and the outer faces of the projections conform in curvature to the curvature of the nose of 65 the shell so as not to arrest or deflect the projectile in its flight.

The message shell is projected from a cannon at the sending station which cannon may be of any desired form utilizing powder 70 for propulsion of the shell or compressed air or other motive fluid. The shell has a rotational movement imparted thereto by the usual rotating bands 14.

The receiving station comprises a wall or 75 supporting structure 16 forming a support for a series of spring buffers 17. In front of the spring baffles is a plate 18 to which is attached a cushion or mattress 19. Spaced forwardly from the cushion are vertical 80 rods 20. To the front and the rear of the rods 20 are a series of superimposed blocks 21 made up of felt, wool or other suitable fiber interspersed with wire netting 22 which retain the mass of felt cushion material together and make the block more 85 resistant to the passage of a shell therethrough. The blocks 21 are retained in position by clips 23 which are slidably mounted on rods 20. The construction described 90 permits the removal of blocks which possibly may be so badly damaged by the impact of shells as to be worthless. The blocks can be independently removed so as to permit the rebuilding of portions of the receiving station without tearing down the entire 95 structure.

Passing through the blocks 21 from front to rear are a series of cords 24 made up of braided linen or other suitable cord woven 100 with wire. The cords are fastened in any suitable manner at the rear face of the rear blocks 21 and at the front face are frayed out so as to form a series of depending tassels 25.

It will be understood that elements 17, 18, 19 and 21 as a whole form a resilient cushion or buffer at the receiving station to bring the shell to rest without fracturing or injuring the same.

The shells approach the forward face of the receiving station with a combined move-

105

110

ment of translation and rotation, and the rotation movement of the shell causes the entangling pins or projections 13 to become entangled in the depending tassels 25.

5. Thereafter the shell is brought to rest by the cushioned baffle device and finally the shells are suspended from the depending tassels as shown in Fig. 1. The shells can then be removed by the recipients and the 10 messages or mail matter therein removed by the removal of the rear closure 11. This is effected by means of a spanner or other suitable tool.

15 Should the pins become so entangled in the tassels that it is impossible to remove the shell, or should the nose or pin portion be damaged so as to require replacement, the part of the nose portion 12 carrying the pins can be unscrewed from the threaded 20 nose section 12^a which forms a closure for the front of the shell. A new pin carrying part can then be applied and the shell casting be used a plurality of times.

I claim:

- 25 1. A message shell comprising a hollow container projectile, said hollow portion of said projectile being clear of mechanism to provide the maximum space for carrying messages, said projectile having entangling pins which extend outward from the curved nose portion of the shell for entangling the shell at a receiving station.

30 2. A message shell comprising a projectile having a hollow interior portion to receive the messages, a removable closure therefor, and a plurality of fixedly mounted externally disposed entangling pins which extend outwardly from the body of the nose portion, said pins being adapted 40 to entangle in and suspend the shell at the receiving station.

35 3. A message shell comprising a three-part projectile including a removable closure, a main hollow body portion and a

45 curved nose portion, and externally mounted entangling pins carried by the nose portion for entangling the shell at the receiving station.

4. A message shell comprising a projectile having a hollow main part and a removable nose portion, and a plurality of entangling pins upon said nose portion for entangling and suspending the shell by the 50 nose portion thereof.

5. A message shell comprising a projectile having a hollow interior and a plurality of entangling pins at the nose portion of the shell for entangling and suspending the shell at the receiving station, said pins extending outwardly from 60 the nose portion and having their exterior ends curving to conform to the curvature of the nose portion of the shell to reduce the wind resistance of same when in flight.

6. A message shell comprising a hollow 65 body portion and a nose portion, said nose portion having a peripheral recess, a plurality of entangling pins extending perpendicularly to the surface of the recessed nose portion and having their ends flush with 70 the curved developed surface of the non-recessed part of the nose portion, said pins being adapted to entangle the shell at a receiving station.

7. In a message shell, in combination, a 75 hollow message carrying projectile, having a curved nose portion, a plurality of entangling pins extending substantially perpendicularly to the shell body at the nose portion thereof to entangle the shell at the 80 receiving station, said pins being constantly extended while the projectile is passing through the gun and while the same is in flight.

In testimony whereof I hereunto affix my 85 signature.

CARLO SERRA.
